UNITED STATES PATENT OFFICE

THOMAS D. HOPKINS, OF MONTGOMERY, ALABAMA

INKSTAND AND BOTTLE

Application filed January 6, 1932. Serial No. 585,103.

This invention relates to ink bottles or wells and the general object of the invention is to provide an ink bottle which may be used as ordinary ink wells are used or used for the purpose of filling fountain pens.

A further object is to provide a reservoir constituting a base for the ink well, and provide means whereby the ink in the reservoir may be allowed to flow into the ink well it-
10 self or cut off therefrom so that the ink well may be replenished whenever desired.

A further object is to provide means af-
fording access to the ink well which will prevent fountain pens, when inserted in the ink
15 well, from being withdrawn therefrom with ink thereon, thus inking the fingers of the person using the pen.

A further object is to provide an ink well and a reservoir therefor, the ink well being
20 provided with a lateral opening through which a pen may be inserted and provided with a rotatable member mounted within the well proper having an ink containing cham-
ber or pocket which, upon a rotation of the
25 stopper or member, may be brought into con-
junction either with the opening leading to the reservoir or with the opening through which a pen may be inserted or to an inter-
mediate position where all evaporation of the
30 ink will be prevented.

Other objects will appear in the course of the following description.

My invention is illustrated in the accom-
panying drawing, wherein:—

Figure 1 is a longitudinal sectional view
35 through an ink well constructed in accordance
with my invention;

Figure 2 is a section of the line 2—2 of Fig-
ure 1.

Referring to the drawing, 10 designates a
40 reservoir which is preferably made of glass,
though it may be made of any other suitable
material and which may have any other de-
sired form, this reservoir constituting the
45 base for the ink well proper. This reservoir
is formed to provide a cylindrical well 11
which extends downward and inward at an
inclination, as for instance, an inclination of
45° to the longitudinal axis of the reservoir
50 base 10.

One wall of this cylindrical barrel 11 is
formed with an opening 12, defined by the
outwardly extending walls 13 which are
formed with an annular recess 14 within
which is received the bead 15 of a rubber cup
55 16. The walls of this cup extend downward
and inward in the general form of a cone
and the bottom of the cup is formed with a
slit 17. It is to be understood that this cup
is sufficiently elastic and flexible as to permit
60 a pen to be inserted through the slit 17 with-
out material impediment, the elasticity of
the cup causing the slit to close. The angle
of the sides of the cup is such that the pen
65 is guided easily into the ink well.

Opposite the opening 12, which opening
12 is on the upper side of the cylindrical ink
well 11, there is formed an opening 18, lead-
ing into the reservoir 10. Disposed within
the cylindrical ink well 11 is a rotatable ele-
ment which I will call a stopper and which
is designated generally 19. This is provided
with the hard rubber head 20 which extends
over the flange at the outer end of the mem-
ber 11 and fits closely against this flange.
70 The member 19 is cylindrical and fits snug-
ly within the ink well 11 and is formed at
one point with the chamber or pocket 21
which intersects the surface of the cylindri-
cal stopper 19 so that when this stopper is
75 rotated in one direction, this pocket 21 will
come into register with the opening 12 and
when the stopper is turned in the opposite di-
rection and half way around, the upper por-
tion of this pocket or chamber 21 will regis-
80 ter with the opening 18. In the last-named
position, and upon tipping the reservoir 10,
the ink within the reservoir may be caused
to flow into the pocket 21. Then by turn-
ing the stopper so as to carry the pocket 21
85 out of register with the opening 18, the ink
will be cut off.

When this stopper is turned into such po-
sition that the pocket 21 is in register with
the opening 12, then a pen may be inserted
90 through the funnel or rubber cup 16 into the
pocket to secure ink for the pen. It will be
seen that when the stopper is turned half
way around so that the chamber or pocket 21
is carried out of alignment with either of the
100

openings 12 or 18, then the ink within the pocket is prevented from evaporation and the ink receptacle is entirely closed. Inasmuch as preferably the receptacle 10 and the ink well 11 are made of glass, it is obvious that the user may see just where the pocket 21 is located. Preferably, though not necessarily, the stopper 19 will be made of cork, hard rubber, or glass. Of course, the stopper 19 will fit the opening in the cylindrical member 11 sufficiently tightly so that no ink will escape and yet will not so tightly but that the stopper may be readily turned to bring the pocket 21 into its operative or filling position. Preferably, the pocket 21 will contain just enough ink to fill an ordinary fountain pen.

A particular function of the cup 16 with the slit 17 is to squeeze off the ink from a pen holder either a fountain pen holder or an ordinary pen holder which has been dipped too far into the ink in the pocket.

This device is particularly adapted for filling fountain pens. The present type of bottom necessitates immersing the lower end of a fountain pen in the ink and a very careful cleansing afterwards or else the ink is transferred to the fingers of the user. With my ink well, this soiling of the lower end of the pen is entirely prevented for the reason that the cup 16 acts to squeeze the ink off of that portion of the pen above the nib.

The fresh ink supply may be instantly brought up into position by simply turning the stopper and if a dipping pen is used, the surplus is discharged back into the bottle by another turn of the stopper. There is no drying, therefore, of the ink nor evaporation.

The bottle neck is of such character that when the stopper is turned to a point where the ink chamber 21 is directly downward, the chamber will open directly into the reservoir or body of the bottle, and with a slight tip, this chamber 21 may be filled. Then when the cork is slightly turned, the filled chamber 21 is turned off from both the contents of the bottle and from the filling opening 12. At the same time, the position of the filled chamber may be observed at all times.

While I have illustrated one embodiment of this ink bottle or stand, I do not wish to be limited to this particular embodiment as obviously the reservoir or body of the reservoir may be of any desired form and many changes might be made in the details of construction and arrangements of the parts without departing from the spirit of the invention as defined in the appended claims.

It will, of course, be understood that the ink bottle or reservoir may be initially filled by removing the stopper and filling through the cylindrical well on which the stopper is disposed. This bottle is particularly designed to be used by manufacturers of ink instead of the ordinary bottle.

I claim:—

1. In an ink stand, a reservoir, a cylindrical ink well extending down into the reservoir at an angle to the longitudinal axis thereof, the wall of said well having an opening below the top of the reservoir, and an opposite pen filling opening above the top of the reservoir, a stopper manually rotatable within the neck of the well and having a chamber therein, open upon the side of the stopper, the chamber being brought into registry with the opening leading into the reservoir or with the opposite opening upon a rotation of the stopper. 70

2. An ink stand of the character described, comprising a body constituting a base and constituting a reservoir for ink, a cylindrical well extending downward into said reservoir at an angle to the longitudinal axis of the reservoir, said well having an opening in its side wall opening into the reservoir and a relatively large pen filling opening in its side wall disposed above the top of the reservoir and on the opposite side of the well and opposite from the first-named opening, a rubber cup disposed within the last named opening, the cup having essentially the form of a cone extending downward and centrally in said opening and at its apex being formed with a slit through which a pen may be inserted, a cylindrical stopper fitting within the cylindrical well and rotatable therein, and having a chamber formed in it opening upon the circumferential face of the stopper, the stopper being rotatable in opposite directions to carry said chamber into a position to register with the opening in the reservoir or with the pen filling opening. 80 85 90 95 100

In testimony whereof I hereunto affix my signature.

THOMAS D. HOPKINS.
